GREY W. WISWELL, OF PILOT KNOB, MISSOURI.

Letters Patent No. 86,617, dated February 2, 1869.

IMPROVEMENT IN STOP-VALVES FOR STEAM-GENERATORS.

The Schedule referred to in these Letters Patent and making part of the same.

To all whom it may concern:

Be it known that I, GREY W. WISWELL, of Pilot Knob, in the county of Iron, and State of Missouri, have made certain new and useful Improvements in Gauge and Stop-Cocks for Steam-Boilers; and I do hereby declare that the following is a full and clear description thereof, reference being had to the accompanying drawings, and to the letters of reference marked thereon.

It is well known that in practice the ordinary gauge-cock, as used to determine the height of water or steam in steam-boilers, is liable to leak or jam, or otherwise to be seriously damaged, thus becoming non-utile; and as these things frequently and generally occur while the boiler is in use, it is plain that it becomes a matter of great importance to so arrange the gauge-cock that it may be readily repaired or replaced without throwing the boiler out of operation.

To accomplish this, I have arranged the said gauge-cock with a stop-cock, and thus I am enabled to shut off the steam from the gauge-cock, and remove it for repairs, or replace it, and then, by turning on steam through the stop-cock, the parts are again in working-order.

To enable those skilled herein to make and use my said invention, I will now more fully describe the construction and operation thereof, referring to—

Figure 1, as an elevation; to

Figure 2, as a vertical transverse section.

I construct the stop-cock A in any of the ordinary forms, and arranging on the rear end the screw-threads a , by means whereof the cock is secured to the skin of the boiler.

In the form of gauge-cock and stop-cock shown in the drawings, I have used the ordinary conical plug A', arranged with central aperture a' , which, when in the direction of the longitudinal axis of the parts, opens communication between the boiler and gauge-cock, and when, by the handle B, the plug A' is turned, (in

an angle of ninety degrees,) the said communication is cut off.

The stop-cock A has the chamber C, at the end whereof I have arranged the screw-threads c , to receive the gauge-cock D and to connect the parts A and D.

The gauge-cock D consists of the housing D' and valve E, the valve having the seat e at the rear end of D'.

In the housing D' is the vertical hole d for the discharge of water or steam.

The valve-stem e' is cut, by either diminishing its diameter, or by making it of triangular section, so that when the valve E is forced back from its seat the steam may pass within the housing D' and out of the hole d .

The valve E has the knob e'' , as usual.

The operation of said gauge is as follows:

The pressure of steam in the boiler holds the valve E against its seat, e . If now the operator forces said valve back from its seat, then steam or water will enter the housing D' and issue at d , indicating the water or steam-level, as usually required.

If, then, the cock D becomes leaky or is jammed, or is otherwise disabled, I close the stop-cock A, by turning the handle B, as aforesaid, and then unscrew or disconnect the gauge-cock D. Then the gauge-cock may be repaired or replaced; and when this has been done, the stop-cock A being opened, the parts are again operative.

Having thus fully described my invention,

What I claim, is—

1. The combination of the stop-cock A and gauge-cock D, substantially as set forth.
2. The arrangement of the stop-cock A, chamber C, and valve E, of the gauge-cock D, substantially as set forth.

GREY W. WISWELL.
